SUBMERGED WATER HEATER

Harry L. Madorin, Chicago, Ill.

Application June 25, 1934, Serial No. 732,194

11 Claims. (Cl. 122—32)

This invention relates to a cleaning mechanism and tube arrangement for submerged water heaters and the like.

Submerged hot water heaters and like devices for treating or conveying liquids are frequently arranged with a bank of parallel conduit tubes. Such tubes generally communicate at their adjacent ends by means of headers or like chambers into which the tubes project and to which they are secured. The header or chamber at one end of the bank of tubes is generally relatively accessible, but that at the other end is frequently in a treating chamber or otherwise inaccessible. If the treated or conveyed liquid such as water contains impurities, sludge, dirt, suspended matter, scale-forming material and the like, the impurities or scale formed settle not only in the tubes but also in the header chambers. My invention contemplates a ready and easily operable means for cleaning the tubes and accessible header or chamber, and also the inaccessible header. It also contemplates an improved tube supporting arrangement.

It is an object of the invention to provide a cleaning device for cleaning the tubes and headers of a liquid conveying or treating unit such as a submerged hot water heater.

It is a further object to provide for cleaning an inaccessible header in such a unit by a mechanism having its controlling parts exposed and accessible for ready operation.

It is a further object to provide an improved tube support for the tubes of a submerged hot water heater or the like, to increase the rigidity of the structure.

It is a further object of the invention to provide a new and improved cleaning device for liquid conveying or treating units which may be readily and cheaply constructed, which may be easily and readily operated, but which is wholly durable and efficient in operation.

It is a further object of the invention to provide a cleaning device which may be readily applied to the various existing types of submerged water heater units.

It is a further object of the invention to provide a cleaning mechanism which when applied to a heater unit does not impair the heat transfer capacity thereof.

Other objects and advantages of the invention will be apparent from the following description, taken in connection with the drawing, wherein there is specifically set forth certain preferred embodiments of the invention.

In the drawing wherein like reference numerals refer to like parts throughout,

Fig. 1 is a section through one type of submerged water heater to which the invention has been applied. 5

Fig. 2 is a section through the accessible header along the line 2—2 of Fig. 1.

Fig. 3 is a section through the inaccessible header along the line 3—3 of Fig. 1.

Fig. 4 is a sectional view through a different 10 type of submerged water heater to which the invention has been applied, and

Fig. 5 is a sectional view through the accessible chamber of such modified form of heater, taken along the line 5—5 of Fig. 4. 15

The invention has been shown applied to a water heater of the submerged type wherein one end of the tube bank and one header are within a boiler or the like and are submerged within the water therein, as the cleaning problem with 20 such devices has been particularly acute, due to the precipitation of the impurities in the water being heated and because of the inaccessibility of the submerged header. The invention, however, has general applicability to all equivalent 25 devices through which fluids containing impurities are to be passed.

Referring first to Figs. 1, 2, and 3, plates 10 and 12 represent the front and rear plates, respectively, of a boiler or the like adapted to contain hot water, as indicated at 14. The submerged water heater for heating water for washing, laundering, and similar purposes extends through the front plate of the boiler into the hot water therein, as shown. The submerged 35 heater comprises an inlet conduit 16 by which it communicates with the lower portion of a suitable hot water storage tank, not shown, a front exposed or accessible header casting 18, in-flow tubes 20 and 22, a rear inaccessible header 24, upper out-flow tubes 26, and an outlet conduit 28 by which the heater communicates with the upper portion of the hot water storage tank. 40

Suitably secured to the front plate 10 of the 45 boiler, as by means of welding or the like, as indicated at 30, is a circular ring member 32, internally tapered and threaded to receive the front header casting 18. The header casting is divided internally by a transverse wall 34, the shape of 50 which is best shown in Fig. 2. The transverse wall divides the header casting into independent lower and upper header chambers. The inlet conduit pipe 16 is threaded into the lower portion of the header casting 18 and communicates with 55

the lower header chamber. In-flow pipes 20 and 22 also communicate with the lower header chamber extending therein through the rear side wall of the casting to which they are suitably secured in fluid-tight manner, as by welding or the like. The out-flow tubes 26 extend through the rear side wall of the casting 18 into the upper header chamber, likewise being secured to the casting wall in a fluid-tight manner. The outlet conduit pipe 28 is threaded into the top of the header casting 18 and communicates with the upper header chamber.

The in-flow and out-flow tubes are in communication at their rear ends through the rear inaccessible header 24. The several tubes pass through the forward wall of the header to which they are secured in fluid-tight manner. The header casting 24 is of circular cup shape; and threaded within its tapered rear portion is a plug member 36.

Formed in casting 18 are two lugs 37 which contact and thus support lower in-flow tubes 20 throughout an appreciable portion of their lengths. This supplemental support reduces the strain on the connection between the tubes and the rear side wall of the casting 18, and inasmuch as all of the tubes of the device are secured at their rear ends by header 24, all of the tubes are in effect supported by lugs 37, the entire assembly being thus made stronger.

The arrangement of the tubes with respect to one another is best shown in Figs. 2 and 3. As indicated, there are three in-flow and three out-flow tubes. The two lower in-flow tubes 20 below the transverse wall 34 in front header casting 18, and the three out-flow tubes 26 above the wall are circumferentially arranged within the headers and with respect to the central in-flow tube 22. The transverse wall 34 has an upward extension adjacent the in-flow tube 22, so that the tube is in communication with the chamber below the wall. The several circumferentially arranged tubes converge as they pass from the front to the rear header, as best indicated in Fig. 1.

Threaded into the forward wall of the front header casting 18 are plugs 38 and 38', there being six plugs in all, one for each tube, and each plug being in line with the axis of the tube with which it is associated. The central plug 38' in line with center in-flow tube 22 has a central aperture in which is journaled a rod 40, which passes through tube 22 and is journaled at its rear end in a central bearing formed within the plug 36 for the rear header. Fluid is prevented from escaping through plug 38' along the rod 40 by means of suitable packing material 42, held in position by compression plug 44, threaded into plug member 38'. Pinned to the forward end of rod 40 is a crank member 46 adapted to be hand operated, and secured to the rod as by welding or the like at its rear portion and within the rear inaccessible header 24 is a scraper blade 48. As best shown in Figs. 1 and 3, the scraper member 48 is notched at 50 longitudinally on both sides near its outer end, thereby forming three edges on the scraper end. These edges are preferably serrated, as indicated, to facilitate their operating action.

The operation of the device is as follows:

Normally, water to be heated is brought from the bottom of the hot water storage tank into the submerged water heater through inlet conduit 16, from which it passes into the lower header chamber in the front header, through in-flow pipes 20 and 22, through inaccessible rear header 24, through outflow pipes 26, through the

upper header chamber in front header 18, and to the top of the water storage tank by means of outlet conduit 28. The water is circulated as it is heated, due to the fact that it becomes lighter as it is heated, and tends to pass upwardly through the device. The converging diverging arrangement of the in-flow and out-flow tubes assists in this circulating action, the water passing generally upwardly through the various tubes. The presence of rod 40 within tube 22 does not impair the heating capacity of this tube as the heat transfer takes place along the tube surface with which the rod does not interfere. Dirt, sludge and scale are precipitated out of the water during use into the chambers of the front header 18, the several tubes, and also the rear inaccessible header 24.

By removing plugs 38 access may be had to the two chambers of the front header for cleaning and, these plugs being aligned with their respective tubes, tube cleaners may be inserted in the tubes for cleaning them. Rotation of hand crank 46 rotates scraper blade 48 within the rear inaccessible header 24. The scraper blade during rotation sweeps along the circumferential wall of the inaccessible header and along the faces of the tubes, thus efficiently loosening and cleaning dirt, scale and the like from the rear header chamber. Dirt which accumulates within plug member 36 does no harm as long as sufficient opening is kept within the rear header casting, and such opening will be insured by the scraping action of the scraper 48. The formation of the scraper end facilitates the cleaning action, efficiently removing all foreign matter, regardless of its character. The crank can be rotated in either direction, so that if the scraper should become jammed by movement in one direction it can be reversed. The cleaning operation may be supplemented by the use of acid to loosen the precipitated and deposited foreign matter, if desired, such acid being introduced either through plugs 38 or through a suitable valve connection in outlet conduit 28.

A cleaning operation such as has been described is necessary only at infrequent intervals as the impurities do not tend to accumulate in quantities within the front header chambers or the tubes. Most of the precipitation and accumulation occurs within the rear inaccessible header 24. This header may be cleaned by means of my invention, merely by rotating hand crank 46 without removal of plugs 38. By opening a suitable drain valve in the pipes 16, hot water from the water storage tank may be flushed reversely through the heater while the crank is being rotated to facilitate removal of the sediment dislodged by scraper 48. The rotation of hand crank 46 without removal of plugs 38 is an exceedingly simple operation, and yet by this operation the most inaccessible portion of the device and the portion thereof in which dirt and the like tend to accumulate most rapidly may be efficiently cleaned. Cleaning by rotation of crank 46 may be effected as often as desirable and necessary.

It is apparent that the invention may be readily applied to various forms of fluid conducting or treating devices such as heaters and the like, without departing from the spirit thereof. In Figs. 4 and 5 the invention is shown applied by way of illustration to a submerged hot water heater of a different form. In this embodiment walls 10' and 12' are the front and rear walls of the boiler, as in the case of the embodiment shown in Figs. 1, 2, and 3, and numeral 14' indicates the hot water within the boiler. The 75

submerged heater device for heating laundry water and the like is secured to front plate 10' and extends into and is submerged in part within the hot water 14 of the boiler. The submerged water heater comprises inlet conduit 16' and outlet conduit 28' as in the first described embodiment, and a front tube connecting casting 52 and a rear inaccessible header 54. In this instance, however, but one in-flow tube 56 and one out-flow tube 58 are provided, and both the casting and the header are accordingly generally oval in shape, as best indicated in Fig. 5. The front casting 52 is bolted to the front boiler plate 10' by means of suitable bolts 60, which pass through a flange formed on the casting and are threaded into the boiler plate 10'. A suitable gasket 62 makes the connection fluid-tight. A transverse wall 64 is formed horizontally within the casting, dividing it into independent lower and upper inlet and outlet chambers. In-flow tube 56 and out-flow tube 58 communicate with the lower and upper chambers respectively, through the rear side wall of the casting to which they are secured in a fluid-tight manner. The tubes pass through the forward wall of inaccessible header 54, communicating with the interior thereof, and this header is closed at its rear portion by oval plate 66 secured to the open rear end of the header by means of bolts 68, a suitable gasket 70 being interposed between the parts to insure a fluid-tight connection.

Two plugs 12, similar to central plug 38' of the device shown in Figs. 1, 2, and 3, are threaded into the front wall of casting 52 in line with the axes of the tubes, and are apertured to receive operating rods 74. The rods pass through the tubes and are journaled in the plugs and the plate 66; and the bearing connection in the plugs is rendered fluid-tight by means of packings 76 and supplemental pressure plugs 78, as in the device previously described. Secured to the rear of each rod 74, is a scraper blade 80 having a cutting edge similar in formation to that of the scraper blade hereinbefore described. A crank member 82 serves as the operating means for rotating the rods 74 and the scrapers 80. In this instance the forward ends of the rods are of square cross-section, the crank having a similarly squared socket and being removably associated with the rods for individual operation of either.

In operation, the crank handle 82 is applied first to one and then to the other of the rods 74, each rod being in turn operated to rotate its associated scraper blade 80 to clean out the rear inaccessible header, as in the previously described embodiment of the invention. This operation may be accompanied by reverse flushing of hot water through the device to remove the sediment dislodged, or by the use of acid suitably injected through conduit 28', as may be desired. When it becomes necessary to scrape tubes 58 and 56, and clean the chambers in casting 52, access thereto may be had by removing plugs 72. However, it is necessary to clean in this manner only very infrequently as most of the sediment tends to lodge in the rear inaccessible header which may be cleaned by simple manipulation of the hand crank.

It will thus be seen that by the invention there is provided a ready and efficient means for cleaning devices through which liquids containing impurities which are precipitated are passed. The means for cleaning that portion of the device in which the impurities most readily accumulate may be easily operated without the removal or adjustment of any of the parts. The cleaning

device may be cheaply and readily constructed, and is formed of a minimum of parts. It is durable and readily operable and yet wholly efficient in operation. When the cleaning arrangement is applied to a heater, the heating efficiency is in no way impaired. By keeping the heater clean of dirt and scale and the like, its heat transfer capacity is kept at a maximum at all times.

In conjunction with the cleaning arrangement in the embodiment of Figs. 1, 2, and 3, a supplemental support for the tubes has been provided which aids in supporting and strengthening the entire device. This is of particular importance in connection with the cleaning mechanism which adds weight to the device and which in operation produces strains requiring a strong and firm assembly.

It is obvious that various changes may be made in the specific embodiments of my invention which I have used for illustrative purposes and I therefore do not wish to be limited to the precise construction shown, but only as indicated in the following claims.

I claim:

1. In a water heating arrangement of the submerged type, a plurality of water conveying tubes, a boiler into which the tubes extend, a header within the boiler connecting the tubes at one end, a casting into which the tubes are fitted at their other end, a rotatable rod extending through said casting into the header, a scraper blade mounted on said rod within said header, said blade being formed and mounted for movement within the header through a path to conform to the header interior, and a crank for operating said scraper.

2. In a water heating arrangement of the submerged type, a boiler, a plurality of tubes extending into said boiler, a circular header connecting said tubes within said boiler at a point remote therein from the boiler exterior, a rod journaled in said header and passing through the central portion thereof, a scraper member secured to said rod, said scraper member being arranged to move through a path closely adjacent to the circular interior of the header, and means for operating said rod.

3. In a device for treating fluids, a bank of tubes, a treating chamber into which said tubes extend, a front casting to which said tubes are secured exteriorly of said chamber, supporting lugs extending longitudinally of the tubes from the face of said casting having supporting contact with at least some of said tubes at the bottom thereof, means for securing said casting to said chamber, a relatively inaccessible header connecting said tubes within said chamber, and movable cleaning means within said header operable from the exterior thereof.

4. In combination with a boiler, a submerged water heater comprising a bank of substantially parallel tubes extending into said boiler, a casting to which said tubes are connected exteriorly of said boiler, means connecting said tubes within said boiler, lugs extending longitudinally of the tubes from the face of said casting for directly supporting at least some of said tubes at the bottom thereof, and means for securing the casting to the boiler.

5. In combination with an enclosed heating boiler; a water heater of the submerged type comprising a bank of heater tubes extending into the boiler; a header connecting said tubes within the boiler at a point therein remotely displaced from the boiler exterior; said header having a

- 5 tube supporting wall, a plate wall displaced therefrom, and a connecting cylindrical wall; a casting into which said tubes project externally of the boiler, removable plugs in the casting in alignment with the axes of the tubes; an elongated rotatable rod passing through one of the tubes through the central portion of the header; said rod being journalled near one end in one of said plugs and having operating means on 10 said end and being journalled at the other end in the header plate wall; and a scraper member mounted on the rod within the header for scraping movement across the faces of the tubes and along the cylindrical wall of the headers.
- 15 6. In combination with an enclosed heating boiler; a water heater of the submerged type comprising a bank of heater tubes extending into the boiler; a header connecting said tubes within the boiler at a point therein remotely displaced from the boiler exterior; said header having a tube supporting wall, a plate wall displaced therefrom, and a connecting cylindrical wall; a casting into which said tubes project externally of the boiler, an elongated rotatable rod passing through 20 the central portion of the header; said rod being journalled near one end in said casting and having operating means on said end and being journalled at the other end in the header plate wall; and a scraper member mounted on the rod within the header for scraping movement across the faces of the tubes and along the cylindrical wall of the header.
- 25 7. In combination with a heating boiler, a water heater of the submerged type comprising a bank of heater tubes extending into the boiler, a header connecting said tubes within the boiler at a point therein remotely displaced from the boiler exterior, said header providing an enlarged 30 passageway connecting the ends of the tubes, a casting into which said tubes project externally of the boiler, an elongated rotatable rod passing through one of the tubes, said rod being journalled near one end in said casting and having operating means on said end and being journalled at the other end in said header, and a scraper member mounted on the rod within the header for scraping movement across the faces of the tubes and along the header walls.
- 35 8. In a water heating construction, a heating boiler, a plurality of elongated tubes extending into the interior of the boiler to a point inaccessible to and remote from the exterior thereof, a header connecting the tubes at such inaccessible point within the boiler, the walls of said header defining a connecting passageway between the ends of the tubes of greater size than the cross section of the individual tubes, a cleaner member mounted within the header for opera-
- 5 tube supporting wall, a plate wall displaced therefrom, and a connecting cylindrical wall; a casting into which said tubes project externally of the boiler, removable plugs in the casting in alignment with the axes of the tubes; an elongated rotatable rod passing through one of the tubes through the central portion of the header; said rod being journalled near one end in one of said plugs and having operating means on 10 said end and being journalled at the other end in the header plate wall; and a scraper member mounted on the rod within the header for scraping movement across the faces of the tubes and along the cylindrical wall of the headers.
- 15 9. In a water heating construction, a heating boiler, a plurality of elongated tubes extending into the interior of the boiler to a point inaccessible to and remote from the exterior thereof, a header connecting the tubes at such inaccessible point within the boiler, the walls of said header defining a connecting passageway between the ends of the tubes of greater size than the cross section of the individual tubes, a cleaner member mounted within the header for operative cleaning movement within said passageway through a space greater than the tube cross section, and means for operating the cleaner from outside the boiler. 5
- 20 10. In a water heating construction, a heating boiler, a plurality of elongated tubes extending into the interior of the boiler to a point inaccessible to and remote from the exterior thereof, a header connecting the tubes at such inaccessible point within the boiler, the walls of said header defining a connecting passageway between the ends of the tubes of greater size than the cross section of the individual tubes, a cleaner member mounted within the header for operative cleaning movement within said passageway through a space greater than the tube cross section, and means for operating the cleaner from outside the boiler, said operating means including a rod connected to the cleaner member and extending through one of the tubes to the outside 20 of the boiler.
- 25 11. In a water heating construction, a heating boiler, a plurality of elongated tubes extending into the interior of the boiler to a point inaccessible to and remote from the exterior thereof, a header connecting the tubes at such inaccessible point within the boiler, the walls of said header defining a connecting passageway between the ends of the tubes, a portion of which is disposed at a lower level than any of the adjacent tube portions, a cleaner member mounted within the header for operative cleaning movement within said passageway, said cleaner member being mounted for sweeping movement through said lower disposed portion of said passageway, and means for operating the cleaner from outside the boiler. 25
- 30 12. In a water heating construction, a heating boiler, a plurality of elongated tubes extending into the interior of the boiler to a point inaccessible to and remote from the exterior thereof, a header connecting the tubes at such inaccessible point within the boiler, the walls of said header defining a connecting passageway between the ends of the tubes, a portion of which is disposed at a lower level than any of the adjacent tube portions, a cleaner member mounted within the header for operative cleaning movement within said passageway, said cleaner member being mounted for sweeping movement through said lower disposed portion of said passageway, and means for operating the cleaner from outside the boiler. 35
- 35 13. In a water heating construction, a heating boiler, a plurality of elongated tubes extending into the interior of the boiler to a point inaccessible to and remote from the exterior thereof, a header connecting the tubes at such inaccessible point within the boiler, the walls of said header defining a connecting passageway between the ends of the tubes, a portion of which is disposed at a lower level than any of the adjacent tube portions, a cleaner member mounted within the header for operative cleaning movement within said passageway, said cleaner member being mounted for sweeping movement through said lower disposed portion of said passageway, and means for operating the cleaner from outside the boiler, said operating means including a rod connected to the cleaner and extending through one of the tubes to the outside 55 of the boiler.

HARRY L. MADORIN.
